UNITED STATES PATENT OFFICE.

CHARLES E. ARNESEN, OF SIOUX FALLS, SOUTH DAKOTA.

SHOCK ABSORBER.

Application filed November 21, 1923. Serial No. 676,111.

To all whom it may concern:

Be it known that I, CHARLES E. ARNESEN, a citizen of the United States, residing at Sioux Falls, in the county of Minnehaha 5 and State of South Dakota, have invented certain new and useful Improvements in Shock Absorbers, of which the following is a specification.

This invention relates to certain new and 10 useful improvements in shock absorbers and the primary object thereof is to provide an improved structure which affords easy riding qualities of the vehicle and which effects corresponding easy and 15 gradual checking of rebounding of the springs.

A further object of the invention is to provide a shock absorber which operates with equal efficiency and which can be applied to either the front or rear springs of 20 the vehicle, or to both.

A still further object of the invention is to provide a device of this type which is of 25 simple and economical construction.

The invention has still further and other 30 objects, which will be later set forth and manifested by and in the course of the following description.

In the drawings:

Figure 1, is a side elevation, showing the 35 invention as applied to the front springs of a vehicle;

Figure 2, is a like view, showing the invention as applied to the rear springs of a 40 vehicle;

Figure 3, is a section on line 3—3 of Figure 1;

Figure 4, is a section on line 4—4 of Figure 2;

Figure 5, is an enlarged sectional view of 45 the device shown in Figure 1, and

Figure 6, is a similar view of Figure 2.

In proceeding in accordance with the 50 present invention and referring to Figures 1, 3 and 5 of the drawings, a main cylinder 1 is provided to one side of which a smaller cylinder 2 is secured, a port 3 at the lower ends of the cylinders establishing communication between the two. A piston 4 operates within the smaller cylinder 2 and has a rod 5 connected thereto, the latter sliding through a stuffing box 6. The upper end of the smaller cylinder 2 is equipped with an air port 7. A body of oil 8 is placed 55 within the cylinders. As illustrated in Figures 1 and 3 of the drawings, the cylinders

are attached by bolts 9 to the vehicle frame adjacent to the front of the latter and at an incline, a cable or other suitable connection 10 being employed which at one end is connected to the piston rod 5, and at its opposite end is secured by a clip 11 to the axle 12 which latter supports the elliptical front springs 13. The bottom of the cylinder 1, is closed by a removable plug 24.

In this form of the invention it will be seen that upon rebounding movement of the frame, the piston will engage the part of the liquid in the cylinder 2 and due to the constricted nature of the port 3, the liquid will be slowly forced into the cylinder 1, and will be cushioned by the air which is compressed between the closed top of the cylinder 1 and the surface of the liquid in said cylinder 1. The piston 4 is permitted free upward movement, since the port 7 permits of free escape of air which is compressed by the piston.

In the form of the invention depicted in Figures 2, 4 and 6 of the drawings, the larger cylinder 14 has a check valve controlled port 15, while the smaller cylinder 16 is completely closed at each of its ends. In this construction, the piston 17 has its rod 18 pivoted to a lever 19, which latter is fixedly secured to a shaft 20. The shaft 20 is journaled in bearings 21 carried by the cylinder 14 and has a downwardly inclined lever arm 22 fixedly secured thereto, the lower end of the arm 22 being secured to one end of a flexible strap 23, the opposite end of the strap being attached to the axle housing 24 which latter is connected to the rear springs 25 as is customary in the art. As illustrated in Figure 4 of the drawings, 95 the cylinders 14 and 16 are bolted at 25 to the inner side face of the side bar of the frame 10 at the rear of the latter. In this form of the invention upon rebounding movement of the frame, the piston 17 which engages the surface of the body of oil or other liquid 26 in the cylinder 16 will be held by the strap 23 and will force the liquid through the constricted port 27 into the larger cylinder 14 and upward movement of the liquid in the cylinder 14 will cushion the air in the space between the surface of the liquid and the closed top of cylinder 14.

As shown in Figure 5, an air inlet valve 15' is applied to the upper end of the main cylinder 1, and formed to enable a pump

to be connected thereto to supply compressed air above the oil surface so as to regulate the resistance which the air offers to the piston movement, as desired. The valve 5 15 in Figure 6, is employed for the same purpose.

What is claimed is:-

1. In a shock absorber, a pair of cylinders of varying diameters having a port establishing communication between the lower ends thereof, a piston in the smaller cylinder having a rod extending downwardly through the bottom of the smaller cylinder and the latter having an air outlet at its 15 upper end, means to connect the piston to the front axle of a vehicle, means to support the cylinders from the frame of a vehicle, and a body of liquid in the cylinders.

2. In a shock absorber, a pair of adjacent cylinders having a relatively small port establishing communication between the lower ends thereof, a body of liquid in the cylinders, one of the cylinders having a piston therein operating from above and 25 downwardly against the surface of the

liquid body, the other cylinder having a valve controlled air inlet adjacent its upper end and above the surface of the body of liquid whereby to enable air under pressure to be introduced in the said other cylinder 30 between the surface of the liquid body therein and its top.

3. In a shock absorber, a pair of cylinders of varying diameters having a port establishing communication between the lower 35 ends thereof, a piston in the smaller cylinder having a rod extending downwardly through the bottom of the smaller cylinder and the latter having an air outlet at its upper end, means to connect the piston to the front axle of a vehicle, means to support the cylinders from the frame of a vehicle, a body of liquid in the cylinders, and a valve controlled air inlet adjacent the upper 40 end of the larger cylinder above the surface 45 of the liquid therein.

In testimony whereof I affix my signature.

CHARLES E. ARNESON
